(57) **CLAIM**

The ornamental design for a display screen with graphical user interface, as shown and described.

DESCRIPTION

FIG. 1 is a front view of a display screen with graphical user interface having a first image showing my new design; FIG. 2 is a front view thereof having a second image; FIG. 3 is a front view thereof having a third image; FIG. 4 is a front view thereof having a fourth image; FIG. 5 is a front view thereof having a fifth image; FIG. 6 is a front view thereof having a sixth image; FIG. 7 is a front view thereof having a seventh image; FIG. 8 is a front view thereof having an eighth image; FIG. 9 is a front view thereof having a ninth image; FIG. 10 is a front view thereof having a tenth image; FIG. 11 is a front view thereof having an eleventh image; FIG. 12 is a front view thereof having a twelfth image; and, FIG. 13 is a front view thereof having a thirteenth image. The appearance of the transitional image sequentially transitions between the images shown in FIGS. 1-13. The process or period in which one image transitions to another image forms no part of the claimed design.

The broken line showing of a display screen with graphical user interface is included for the purpose of showing portions of the article which form no part of the claim. The shaded portions within broken lines form no part of the claim. However, white solid line icons shown in shaded portions within broken lines do form part of the claim. The other shaded portions indicate a contrast in appearance and form part of the claim.

1 Claim, 13 Drawing Sheets
